UNITED STATES PATENT OFFICE.

REINOLD BERRENBERG AND ALONZO S. DRISKO, OF BOSTON,
MASSACHUSETTS.

AIR-COMPRESSOR.

No. 852,817.

Specification of Letters Patent.

Patented May 7, 1907.

Application filed March 16, 1905. Serial No. 250,458.

To all whom it may concern:

Be it known that we, REINOLD BERRENBERG and ALONZO S. DRISKO, of Boston, in the county of Suffolk and State of Massachusetts, have invented a new and useful Improvement in Air-Compressors, of which the following, taken in connection with the accompanying drawings, is a specification.

Our invention relates to that class of rotary pumps that is used for compressing air and gases, and consists in certain mechanical devices which may be best understood by reference to the drawings and description, the object being to make a durable and rapid working compressor. This object I attain by the mechanism shown in the accompanying drawings, in which—

Figure 1 is a view of one of my pumps, partly in side elevation and partly in vertical section. Fig. 2 is a longitudinal vertical section. Fig. 3 shows a part of the interior of the casing. Fig. 4 shows details including one of the pistons and parts of the piston guiding rings.

In the drawings A and A¹ represent the sides of the case and B B¹ the cylindrical or drum part of the case within which the working parts operate.

C is an annular water-chamber in which water circulates for the purpose of keeping the machine cool.

The rotating piston carrier E is a solid cylinder except that it has recesses at each end for allowing room for the piston-guiding rings R and R¹. This rotating piston-carrier is mounted upon the journal D, to which it is keyed, and rotates freely with the said shaft. The piston-chamber is cylindrical above the ports G and G¹ and coincides with the periphery of the piston-carrier and is concentric with the journal D. The lower part of the piston-chamber is also cylindrical, but it extends below the piston-carrier, leaving a crescent-shaped space, P,—see Figs. 1 and 2—in which the projecting ends F¹, F², F³ of the pistons F bear and act as pistons. The pistons F work freely in radial grooves made in the piston-carrier, as shown in Fig. 1. The pistons F—F are compounded or laminated

as shown, that is, each piston is composed of a number of plates, each free to slide and adapt itself to the interior of the piston-chamber so that there is much more certainty of having air-tight joints between the

interior of the piston-chamber walls and the 55 working ends of the pistons F—F.

The interior edges of the pistons F—F have projections f, f, see Fig. 2. When the carrier in its rotation takes the pistons into their working positions, then the piston-controlling rings R, R come in contact with the projections f, f, on the pistons and force them outward, thereby causing their outward ends to come in contact with the interior wall of the piston chamber, see Fig. 1 65 F¹ F² F³ and thus cause them to make tight joints with the said walls. The rings R, R have grooves, r, made in them for the reception of anti-friction balls. These balls lie between the outer rings R and the inner rings 70 R¹ and thus prevent friction. The inner rings are free except that they are controlled by the eccentric studs N; these studs are made with stems N¹ eccentric with them so that by turning the stems the studs can be 75 adjusted so as to cause the rings to assume the desired position for controlling the piston F and thus forcing them outward and against the wall of the piston-chamber, as shown in Figs. 1 and 2. The outer and inner rings 80 with their anti-friction balls and one of the laminated pistons F are shown in detail in Fig. 4.

The interior of the wall of the upper part of the piston cylinder is shown in Fig. 3 and 85 has spiral inwardly projecting ribs E¹ which serve to clean off the working ends of the piston F and free them from any grit or other substance that may collect upon them and which would otherwise interfere with the perfect working of the device.

Although we have called this instrument an air-compressor, it may be used for a water-pump or meter and, with perhaps slight alteration, an engine.

The water jacket space C has inlet and outlet openings C¹ and C² which are connected by suitable pipes to a force pump and water tank and so arranged that a continual flow of water is maintained in the said space 100 C. The pump can be operated by a motion-transmitting mechanism connected to the shaft D or by a separate motor if desired.

Claims.

1. A rotary air-compressor, comprising a 105 piston-chamber provided with inlet and outlet ports, a rotating piston-carrier having laminated pistons, and having recesses at

each end; piston-controlling rings located in said recesses; anti-friction balls upon which the said piston-controlling rings run; inner rings constructed for the said anti-friction 5 balls to run upon; and adjustable eccentric studs constructed to hold said inner rings in their desired position; substantially as and for the purpose set forth.

2. A rotary air-compressor, comprising a 10 piston-chamber provided with inlet and outlet ports and having spiral inwardly projecting ribs on its inner periphery; a rotating piston-carrier and pistons, said rotating piston-carrier having recesses at each end; 15 piston-controlling rings located in said recesses; anti-friction balls upon which said

piston-controlling rings run; inner rings constructed for the said anti-friction balls to run upon; and adjustable eccentric studs constructed to hold said inner rings in their 20 desired position; substantially as and for the purpose set forth.

In testimony whereof, we have signed our names to this specification in the presence of two subscribing witnesses, on this tenth day 25 of March A. D. 1905.

REINOLD BERRENBERG.
ALONZO S. DRISKO.
